UNITED STATES PATENT OFFICE.

EDGAR H. COTTRELL AND CHARLES P. COTTRELL, OF STONINGTON, CONNECTICUT, ASSIGNORS TO THE C. B. COTTRELL & SONS COMPANY, OF SAME PLACE AND NEW YORK, N. Y.

APPARATUS FOR FOLDING PAPER.

SPECIFICATION forming part of Letters Patent No. 633,716, dated September 26, 1899.

Application filed March 30, 1897. Serial No. 629,912. (No model.)

To all whom it may concern:

Be it known that we, EDGAR H. COTTRELL and CHARLES P. COTTRELL, of Stonington, in the county of New London and State of Connecticut, have invented a new and useful Improvement in Apparatus for Folding Paper, of which the following is a specification.

This invention relates to that well-known class of folding apparatus the two principal elements of which are a stationary folding table or bed in which there is a slot and a blade which enters the said slot and folds or commences the folding of the paper by driving it into the said slot; and it relates especially to such machines for folding simultaneously several sheets which have been deposited one upon another on such table or bed.

To enable others skilled in the art to make and use our invention, we will first describe it in detail with reference to the accompanying drawings and afterward point out its novelty in claims.

Figure 1 represents a side view of a folding apparatus which is necessary to illustrate our invention. Fig. 2 represents a plan view of the same with parts of the folding-blade omitted to expose other parts of the apparatus to view. Fig. 3 is a vertical section corresponding with Fig. 1, taken in the line 3 3 of Fig. 2. Fig. 4 represents a vertical section corresponding with Fig. 3, but on a larger scale, of the slotted portion of the folding-table and of the folding-blade.

Similar letters of reference designate corresponding parts in all the figures.

A is the folding-table, having in it the slot a, through which works the folding-blade b, carried by the arms B of a rock-shaft B'. The slot a is represented as having its margins rounded off downward in the usual manner to facilitate the passage of the paper into it. On the face of the table A at right angles to the slot a there are a number of raised ribs c, which are intended to correspond in number, width, and position with the number, width, and position of the unprinted marginal spaces included in the width of the sheet to be folded. These ribs project only sufficiently above the table to keep the printed pages from contact with the intervening portions of the surfaces

of the table. The said ribs c are continued in taper form or of a gradually-diminishing depth over the rounded margins of the slot and are prolonged to project downward beyond the edges of the said slot in the form of thin tongues c* c*, between which the folding-blade passes.

The sheets of paper may be fed to the folding-table A by any known or suitable feeding device. Such feeding device is represented by a roller j at the rear or receiving end of the table and may be supposed to be one of a pair of pressure-rollers or one of the rollers of a tape-carrier. Of whatever kind the feeding device may be it should be such that by its action the sheets should be caused to acquire such momentum that after leaving it they will run forward on the table as far as a stop-gage d on or near the farther end thereof, which will stop them in proper position for folding.

For the purpose of confining the front ends of the sheets to the table in the feeding operation, and especially for preventing the curling or turning up of the forward edges or ends of the sheets, there is arranged over the portion of the table in advance of the slot a a shaft k, carrying a number of wheels k', which are arranged over the ribs c of the table, one for each rib. The said shaft k is represented as running in bearings in arms l, which are secured fixedly upon a stationary bar m, secured across the table in the main framing C of the folding machinery. The arms l are so arranged upon the stationary bar m that the wheels will run freely over the fed sheets passing under them and without pressure thereon. The said shaft k is furnished with a spur-gear k², through which it receives such rotary motion that the velocities of the peripheries of the wheels k' are greater than that of the feed of the sheet, the purpose of the said wheels being to prevent the curling up of the heads of the sheets and of smoothing out the sheets as they pass onward on the tables. Under the table there is a pair of pinching-rollers i, which are geared together and suitably driven for the purpose of completing the fold commenced and partly performed in the slot a by the blade b. The gear k² on the

shaft k is represented as deriving motion from a gear on the shaft of one of these pinching-rollers through intermediate gears n on a fixed stud n' , secured in the framing. The 5 prolongations of the ribs c and their tongues $c^* c^*$ extend about the upper parts of the said rollers.

In the folding operation produced by the 10 entry of the blade into the slot a the paper is unavoidably dragged over the table; but the ribs c confine the drag to the unprinted marginal portions of the sheet, and the final action of the blade where the drag would be most severe takes place between the projecting 15 tongues $c^* c^*$, which during such action are the only portions of the table with which the sheet is in contact. The smearing of the printed portion of the sheet is thus prevented.

For the purpose of evening the side edges 20 of a number of sheets successively deposited on the table against the front stop-gage d previous to their being simultaneously folded there is fast upon the table, near one side thereof, a plate e , constituting a stationary 25 guide or gage for one edge of the sheet arranged at right angles to the slot a , and near the other side of the table there is similarly arranged, parallel with e , a similar plate f , which may be called a "jogger," and which 30 may be given a slight movement toward the guide or gage e for the purpose of pushing the successive sheets toward the said gage e . This jogger f is made with a hub f^* , which 35 slides in a guide-slot f' in the table A and which projects downward below the table, where it is fastened by any suitable means, as by a set-screw f^2 , to a rod f^3 , which works in a guide f^4 under the table. Between the 40 said guide f^4 and a nut f^5 , screwed upon the said rod f^3 , there is coiled around the rod a spiral spring f^6 , which tends to draw the jogger f toward the gage e . The rod f^3 is connected with one end of a lever g , which works 45 on a fixed fulcrum g' , secured to one side of the table A . The other end of the said lever is furnished with a roller g^2 , which works against a cam h on a suitable shaft h' , to which rotary motion is imparted by any suitable means. This shaft h' is represented 50 as the shaft of one of the pinching-rollers. The said cam h during every revolution of the shaft h' draws aside the jogger f , widening the space between it and the gage e . The connection between the lever g and the 55 jogger-rod f^3 is so adjusted by nuts f^7 on the portion of the rod f^3 which projects through the said lever that the cam, acting on the other end of the lever, will only permit the spring to draw the jogger toward the gage 60 so far that there is just room between them for a sheet. The rotation of the cam draws back the jogger as often as the sheets are deposited on the table, and every time a sheet is deposited it is knocked or jogged toward 65 the gage e by the action of the spring on the

jogger. In this way the side edges of the several sheets to be simultaneously folded are evened together, and as the front edges are evened against the stop-gage d the sheets are folded uniformly.

It may be mentioned that in a machine for folding simultaneously several sheets which have been successively deposited upon the table the folding-blade would only be operated at intervals after the desired number of sheets had been deposited. A machine so organized, to which this invention is especially adapted, would fold sheets of a length greater than the circumference of the rollers $i i$; but if the cam h for operating the jogger f should be upon the shaft of one of said rollers in a machine organized to fold singly every sheet deposited on the table the length of the sheets folded could not be greater than the circumference of the said rollers.

What we claim as our invention is—

1. In a folding apparatus, the combination of a folding-blade and a folding-table having a slot with rounded margins for the entry of said blade and having upon its face at right angles to the slot a series of raised ribs which are continued of gradually-diminishing depth over said rounded margins, substantially as herein described.

2. In a folding apparatus, the combination of a folding-blade, a folding-table having a slot for the entry of said blade and having upon its face at right angles to its slot a series of raised ribs which are prolonged in the form of tongues beyond the edges of the slot, and pinching-rollers at the back of said slot between which said tongues enter, substantially as herein described.

3. In a folding apparatus, the combination of a folding-blade, a folding-table slotted for the entry of said blade, means for feeding sheets to said table, a rotary shaft arranged across the face of said table, smoothing-wheels upon said shaft running in proximity to the table without pressure thereon, and means for driving said shaft whereby the peripheries of said wheels have a velocity greater than that of the feed of the sheets, substantially as herein described.

4. In a folding apparatus, the combination of a folding-blade, a folding-table slotted for the entry of said blade and having upon its face at right angles to its slot a series of raised ribs, a rotary shaft arranged across the face of said table and smoothing-wheels upon said shaft arranged opposite to said ribs, substantially as herein described.
